UNITED STATES PATENT OFFICE

2,024,763

MACHINE FOR APPLYING FASTENERS TO
ENVELOPESVincent E. Heywood, Worcester, Mass., assignor
to United States Envelope Company, Springfield,
Mass., a corporation of Maine

Application November 1, 1932, Serial No. 640,694

18 Claims. (Cl. 93—61)

The present invention relates to a machine for applying fasteners to envelopes, particularly fasteners of the so-called double button and string type, in which a fastener washer, or button, is provided on the outside of an envelope body to cooperate with a similar button affixed to the envelope flap, with a string having one end secured to the flap button, so that it may be led back and forth between the buttons to effect closure of the envelope.

5

Briefly stated, the invention contemplates the provision in a single machine that is entirely automatic in its operation, of means for removing envelopes, or other blanks, from a suitable supply and presenting them, one by one, in flat condition to a fastener attaching station, at which the fastener buttons and string are applied by suitable mechanism, and means for withdrawing the envelopes from the attaching station, with the buttons and string attached thereto, and delivering them to a suitable stacking device. In addition, the machine provides in combination with the above mentioned instrumentalities, means for automatically rendering the button and string applying devices inoperative, upon failure of the envelopes to feed properly, means for readily adjusting the feed mechanism to handle envelopes of different dimensions and means for counting the completed envelopes delivered to the stacking device. The above and other advantageous features of the invention will hereinafter more fully appear from the following description with reference to the accompanying drawings, in which:—

20

35 Fig. 1 is a view in front elevation of a machine embodying the invention.

Fig. 2 is a view in side elevation of the machine shown in Fig. 1, as viewed from the left.

40 Fig. 3 is a plan view of the machine shown in Fig. 1, with portions removed to show the transfer mechanism.

Fig. 4 is a horizontal sectional view along the line 4—4 of Fig. 1, looking in the direction of the arrows.

45 Fig. 5 is a fragmentary sectional view along the line 5—5 of Fig. 1, looking in the direction of the arrows.

Fig. 6 is a fragmentary view showing, on an enlarged scale, details of the mechanism for operating the envelope transfer disk and stops.

50

Fig. 7 is a fragmentary sectional view of a portion of the parts shown in Fig. 6.

Fig. 8 is a fragmentary view of a portion of the stop mechanism, as viewed from the right 55 in Fig. 6.

Fig. 9 is a fragmentary plan view, partially in section, showing on an enlarged scale the fastener attaching devices with reference to the envelope gaging and counting devices.

Figs. 10 and 11 are fragmentary sectional views 5 along the lines 10—10 and 11—11 of Fig. 9, respectively.

Like reference characters refer to like parts in the different figures.

General description of machine

10

Referring first to Figs. 1 and 2, the machine generally comprises a table 1 providing upwardly extending brackets 2 for carrying a downwardly inclined feed board 3. The feed board 3 serves 15 to support a plurality of envelopes, or other suitable blanks 4, to which it is desired to attach fastening devices of the character previously referred to. The board 3 cooperates with an adjustable stop plate 5, which serves to maintain 20 the envelopes 4 in a substantially vertical position with their longitudinal edges bearing on the board 3, a weight 6 slidably mounted on the board 3 serving to press the stack of envelopes toward the stop plate 5, with the innermost envelope 4 resting on a flexible retard or separator 3a carried by the board 3.

The envelope 4 nearest the vertical stop plate 5 is adapted to be engaged by a pair of feed wheels 7, 7, preferably providing segmental selectors 7a surfaced with frictional material, so that each revolution of the feed wheels 7 serves to move the innermost envelope 4 downwardly, past the flexible retard 3a, towards a vertical feed plate 8 and into the bite of cooperating rolls 46. 30 After an envelope 4 is cleared from the feed wheels 7 and rolls 46, it is free to fall along the face of the plate 8, a spaced guide plate 9 serving to prevent the envelope from falling away from the face of the feed plate 8. As an envelope 40 passes between the plates 8 and 9, its downward movement is arrested by the engagement of its lower edge with a number of stops 10 adapted to project through slots 11 provided in the plate 9, see Figs. 6 and 8. The stops 10 are carried by 45 arms 12, all mounted on a cross shaft 13 adapted to have rotative movement imparted thereto through a crank 14. As will be hereinafter described, the crank 14 is adapted to be given an oscillatory movement, so that the stops 10 are 50 withdrawn from beneath an envelope 4 following the presentation of an envelope to the fastener attaching station and its return with the fastener devices applied thereto.

After an envelope 4 is arrested by the stops 10 55

in engagement with the feed plate 8, it is operated upon by a transfer disk 15, the disk 15 being adapted for oscillatory movement about the axis of a substantially vertical shaft 16, combined with angular movement about a horizontal shaft 17, on which a standard 18 carrying the disk 15 and shaft 16 is pivotally supported. As will hereinafter appear, the mechanism controlling the oscillatory movement of the disk 15 with the shaft 16, and the pivotal movement of the standard 18 about the shaft 17, is so timed that when an envelope 4 comes to rest on the stops 10, the transfer disk 15 is in a retracted position, so that its periphery is separated from the surface of the envelope. Following this, the standard 18 is swung inwardly toward the plate 8 to cause the periphery of the disk 15 to engage the envelope. Rotation of the disk 15 in one direction with the shaft 16 then causes the envelope to be projected bodily with its sealing flap 4a extended in the direction of an anvil 19, see Fig. 3, forming part of the fastener attaching mechanism, herein-after described. During the attachment of the buttons and string to the envelope, the disk 15 remains stationary, with the standard 18 maintaining the disk in engagement with the envelope, as shown in Fig. 1. Upon completion of the fastener attaching operations, rotation is imparted to the disk 15 in the opposite direction, thereby returning the completed envelope to its previous position in which it is supported by the stops 10, after which the standard 18 is swung away from the plate 8 to disengage the disk 15 from the envelope. Following disengagement of the disk 15 from the envelope, retraction of the stops 10 permits the envelope to resume its downward travel to a stacking device indicated generally by the reference character 20. Movement of each envelope by the transfer disk 15 is accompanied by gaging, herein-after described.

As best shown in Figs. 1 and 6, the stacking device 20 consists of a series of continuously driven belts 21, downwardly inclined, the belts 21 at their upper ends extending underneath and somewhat beyond the lower edge of the feed plate 8, with combined forwarding and lifter rolls 22 cooperating with the upper faces of the belts 21. With the belts 21 moving away from plate 8 in the direction of the arrows in Fig. 1, it is evident that as the lower edge of a completed envelope reaches the belts 21 following release by the stops 10, the belts will draw the envelope beneath the rolls 22, thereby causing it to move flatwise on the belts 21, with its flap extended. As each envelope 4 moves on to the belts 21, notches 22a on the rolls 22 lift the envelopes previously stacked from the belts 21 to permit free travel of the envelope, movement of the envelope being arrested by means of a series of rods 23 extending upwardly between the several belts 21. Therefore, as successive envelopes are delivered to the belts 21 and engage the rods 23, the envelopes will build up in a stack supported by the rods 23, as indicated in Fig. 1. Having described the general functioning of the envelope feeding, transfer and stacking devices, there will next be described the arrangement for driving these several mechanisms in timed relation, so that each complete operating cycle of the machine will result in the delivery of an envelope to the fastener attaching station, its withdrawal with the fastener devices attached thereto and the stacking of the previously completed envelope.

Envelope feeding and transfer mechanism

As best shown in Fig. 1, the source of power for driving the entire machine is illustrated as an electric motor 24 suitably connected, as by a chain 25, to a shaft 26 mounted on a sub-base 1a at right angles to the shaft 17. As best shown in Figs. 4 and 7, the drive shaft 26 carries a bevel gear 27 in mesh with a bevel gear 28 mounted on a countershaft 29 extending parallel to the shaft 17 on which the standard 18 is pivotally mounted. A sleeve 30 is rotatably mounted on the shaft 29, and carries a bevel gear 31 in mesh with a second bevel gear 32 on the drive shaft 26 facing oppositely with respect to the bevel gear 27. Consequently, with the gearing shown, the shaft 29 and sleeve 30 are driven from the shaft 26 in opposite directions of rotation, although at the same speed, for a purpose which will hereinafter appear.

The bevel gear 32 on the drive shaft 26 is also in mesh with a bevel gear 33 mounted on a countershaft 34 in axial alinement with the countershaft 29, so that the shaft 34 is driven in unison with the shaft 29 and sleeve 30. The end of the shaft 34 carries a crank arm 35 having a roll 36 at its end adapted to be received in the slots 37 of a disk 38 mounted on a shaft 39 in axial alinement with the shaft 17, the arm 35 and disk 38 constituting a Geneva motion for imparting intermittent rotation to the shaft 39 from the drive shaft 26. As best shown in Figs. 2 and 5, a sprocket wheel 40 turnable with the Geneva disk 38 is connected to a shaft 41 carrying the feed wheels 7 by a chain 42 passing around a sprocket wheel 43a mounted on a cross shaft 43 and a second chain 44 passing around sprocket wheels 43b and 45 on the shafts 43 and 41 respectively.

The relation between the sprocket wheels 40, 43a, 43b and 45 is such that for each partial revolution of the shaft 39 through the Geneva motion, the feed wheels 7 will have one complete revolution imparted thereto from the position shown in Fig. 1. Therefore, once during a portion of each complete revolution of the drive shaft, the selectors 1a on the feed wheels 7 will draw the lower portion of the innermost envelope 4 past the flexible retard 3a and project it downwardly into the space between the feed plates 8 and 9, pull rolls 46 cooperating with the feed wheels 7 serving to pull the envelope past the retard 3a and direct the envelope in a substantially vertical plane. After the feeding of an envelope 4, the feed wheels 7 come to rest in the position shown in Fig. 1, and are stationary during the remainder of the operating cycle represented by one complete revolution of the drive shaft 26.

After an envelope is released from the bite between the selectors 1a and rolls 46, its downward movement along the face of the feed plate 8 is arrested by the stops 10, at that time in the position shown in Fig. 6, with their ends extending through the slots 11 in plate 9 and butting against the feed plate 8. The outline of an envelope 4, as positioned on the stops 10, is shown in dotted lines in Fig. 5, with the flap 4a of the envelope extended in the direction of the anvil 19. As best shown in Figs. 6 and 8, the stops 10 are maintained in the envelope arresting position by means of a rod 47 connected by a swivel block 47a to the crank 14 extending from the cross shaft 13, on which the arms 12 carrying the stops 10 are mounted. The rod 47 extends down-

wardly and provides at its lower end a forked portion 48 embracing the sleeve 30 and carrying a roll 48a bearing on the surface of a cam 49 mounted on the continuously driven sleeve 30, 5 see Fig. 7. The cam 49 is so timed that the stops 10 hold an envelope in arrested position until it is engaged by the transfer disk 15, and projected by the latter in the direction of the anvil 19. The stops 10 are then retracted so that upon re- 10 turn of the envelope by the disk 15, following the fastener attaching operation and withdrawal of the disk, the completed envelope will be free to move toward the conveyor belts 21 of the stacking device.

15 Since the sleeve 30 is driven in unison with the main shaft 26, it follows that once during each operating cycle of the machine, the stops 10 will be projected into the path of an envelope delivered by the feed wheel 7, and then retracted 20 prior to the return of a completed envelope and its release by the disk 15.

As previously pointed out, the standard 18 carrying the transfer disk 15 is pivotally mounted on the shaft 17, and this mounting, as best shown 25 in Fig. 5, allows for oscillatory movement of the disk 15 independently of pivotal movement of the standard 18. To this end, the lower end of the standard 18 provides a bracket portion 50 bridging the drive shaft 26, with split bearings 30 51 embracing the opposed end portions of the shaft 17 and of the shaft 39 in alignment therewith. Consequently, the standard 18 is adapted for pivotal movement about the aligned axes of the shafts 17 and 39, with the angular position of 35 the standard 18 determined by a pair of links 52 and 53. As best shown in Fig. 6, one end of link 52 is pivotally connected to the standard 18, while one end of link 53 is mounted on a fixed pivot 54, with the other ends of both links pivot- 40 ally connected by a pin 55. The pin 55 is also carried by the head 56 of a longitudinally adjustable rod 57 extending downwardly, with its lower end providing a forked portion 58 embracing the sleeve 30, see Fig. 7. The fork 58 carries 45 a roll 59 bearing on the surface of a cam 60 mounted adjacent to the cam 49 and turnable with the sleeve 30. By reason of the fact that the link 53 has one end thereof mounted on the fixed pivot 54, vertical movement of the rod 57 by the cam 60 is adapted to impart an oscillatory movement to the standard 18 about the axis of the shaft 17. The cam 60 is so timed that following the positioning of an envelope by the stops 10, the standard 18 will be swung to the left, as 55 viewed in Fig. 6, to cause the then stationary transfer disk 15 to engage the surface of the envelope and press it against the feed plate 8. The standard 18 remains in this position during the transfer of the envelope by oscillatory movement 60 of the disk 15, as will next be described, after which the standard 18 is swung to the right to release the completed envelope.

As previously pointed out, the disk 15 is rotatably mounted on a shaft 16, the shaft 16 being mounted in bearings 18a provided by the standard 18, as shown in Fig. 5. The lower end of shaft 16 carries a bevel gear 61 in mesh with a bevel gear 62 carried by a sleeve 62a freely rotatable on the shaft 17, about which the standard 18 swings. As best shown in Fig. 6, the sleeve 62a provides a segmental disk portion 63 with a radial slot 63a adapted to slidably receive rolls 64a and 65a carried by crank arms 64 and 65, respectively. As best shown in Fig. 4, the arm 64 carrying the roll 64a is rotatable with the shaft

29, while the arm 65 carrying the roll 65a is rotatable with the sleeve 30. Therefore, since the shaft 29 and the sleeve 30 are driven in opposite directions of rotation from the shaft 26, movement of the rolls 64a and 65a in the slot 5 63a of the Geneva disk 63 is adapted to impart oscillatory movement to the sleeve 62a.

With the parts in the position shown in Fig. 6, it is evident that turning of the shaft 29 through part of a revolution will result in the roll 10 64a imparting rotation in one direction to the transfer disk 15, through the Geneva motion and its connection through the bevel gears 61 and 62 to the shaft 16. As the roll 64a turning in a counterclockwise direction, as viewed in Fig. 6, 15 leaves the slot 63a, the disk 15 will come to rest. At this moment, the roll 65a on arm 65, turning in a clockwise direction with the sleeve 30 is approaching the slot 63a and shortly after the roll 64a has cleared the slot, the roll 65a enters the 20 same. Continued movement of the arm 65 with the sleeve 30 causes the roll 65a to turn the Geneva member 63 in the opposite direction from which it was previously turned by the roll 64a, thereby reversing the direction of rotation of 25 the transfer disk 15. Following this, the disk 15 comes to rest as the roll 65a leaves the slot 63a.

As a result of the above described functioning of the double Geneva motion, intermittent rotative movement is imparted to the transfer disk 30 15, first in one direction and then in the other, with a dwell between each rotative movement. The double Geneva motion is so timed with reference to the cam 60 that both rotative movements of the disk 15 occur while the standard 18 is in 35 such a position as to maintain the periphery of the disk 15 in frictional engagement with an envelope. Therefore, an envelope supported by the stops 10 is first projected toward the fastener attaching station, with the anvil 19 entering between the extended flap 4a and the body of the envelope 4, as shown in dot and dash lines in Fig. 5, after which the envelope remains stationary during the fastener attaching operations, followed by withdrawal of the envelope 45 to a position clear of the anvil 19 upon reversal of the disk 15. The disk 15 then remains stationary during the swinging movement of the standard 18 away from the plate 8 to permit release of the finished envelope by the stops 10. 50 The above described cycle of movements of the disk 15 takes place during each complete revolution of the drive shaft 26, and there will next be described the gaging devices cooperating with the disk to insure proper registration of each envelope 55 with the anvil 19 and stacking device 29.

Envelope gaging mechanism

As best shown in Figs. 5 and 9, the stationary anvil 19 carries a gage 66 for the purpose of 60 registering the extended flap and rear wall of each envelope 4 with the fastener attaching mechanism cooperating with the anvil 19 in a manner hereinafter described. As shown, the gage 66 is in the form of a finger projecting laterally from the upper surface of the anvil, so that when the disk 15 moves an envelope onto the anvil as previously described, the gage finger will be engaged by the upper edge of the rear wall of the envelope, as indicated in dot and dash 65 lines in Fig. 5. In order to provide for the proper registration of envelopes of different dimensions on the anvil 19 by the transfer disk 15, the gage 66 is adjustable longitudinally of the anvil 19. To this end, the gage provides a slot 66a, through 70 75

which passes a set screw 67, so that the gage 66 can be secured at different distances from the beveled nose of the anvil 19.

In order to insure that the gage 66 will be always positively engaged by an envelope in proper registration with the fastener attaching devices cooperating with the anvil 19, the transfer disk 15 is so connected to the shaft 16 as to insure that the disk will always tend to move an envelope a little beyond the gage 66, even when the gage 66 is set at its maximum distance from the axis of the shaft 16. As best shown in Fig. 6, the upper end of the shaft 16 carries a collar 16a, and a spring 68 encircling the shaft below the collar 16a serves to press friction plates 15a into engagement with the upper and lower faces of the disk 15. Normally the pressure of the spring 68 is sufficient to cause the plates 15a to turn the disk 15, but when an envelope encounters the gage 66 on the anvil, the resistance to further travel of the envelope causes the friction plates 15a to slip, while the disk 15 remains stationary. The above described frictional connection between the disk 15 and its shaft 16 insures that each envelope will always be accurately registered by the gage 66, without any tendency for the disk 15 to buckle the envelope after its movement has been arrested by the gage.

When the disk 15 is turned in a counterclockwise direction, as viewed in Fig. 9, to withdraw a completed envelope from the anvil 19, the movement of the envelope away from the anvil 19 is adapted to be arrested by a second gage 69 extending through one of a series of slots 69a in the feed plate 8, see Fig. 2. The purpose of the gage 69 is to bring each completed envelope to rest on the feed plate 8, with its bottom edge in proper registration with the belts 21 of the stacking device 20, prior to the release of the envelope by the stops 10. The gage 69 provides a shank portion longitudinally adjustable in a holder 70a that is swiveled on a pivoted gage bracket 70, the detail construction and function of which will be hereinafter described. It is evident from a consideration of Fig. 2 that the several gage slots 69a in the feed plate 8 are adapted to receive the end of the gage 69, the swivel mounting of the holder 70a permitting the gage to be received in any one of the slots 69a. Since the slots 69a are overlapping, it is obvious that the gage may be set to register envelopes having a wide range of lengths. The amplitude of the oscillatory movement of the transfer disk 15 is such that the disk is adapted to move a completed envelope so that its rear edge will strike the gage 69 even when the latter is mounted in its position farthest removed from the axis of the shaft 16. Thereafter, the frictional drive of the disk 15 from the shaft 16 operates in the same manner to prevent buckling of the envelopes, as described above with reference to the anvil gage 66. Thus the gages 66 and 69 are adapted to cooperate with the transfer disk 15 in such a manner as to always accurately register the envelopes with both the fastener attaching devices associated with the anvil 19 and the stacking device 20. But before entering into a description of the fastener attaching mechanism, which forms no part of the present invention per se, there will next be described the arrangement contemplated by the present invention for automatically rendering the fastener attaching devices inoperative upon failure of an envelope to be fed by the wheels 7.

Automatic control of fastener attaching mechanism

As best shown in Fig. 3, a shaft 71 extending parallel to and above the drive shaft 26 is adapted to control the operation of a group of button and string attaching devices cooperating with the anvil 19, each complete revolution of the shaft 71 being adapted to cause a complete cycle of operations of the attaching mechanism. A sleeve 72 loosely mounted on the shaft 71 is intermittently driven by a chain 72a through a Geneva movement hereinafter described, and the shaft 71 is adapted to be operatively connected to the sleeve 72 by means of a clutching element 73 slidably keyed to the shaft 71. Movement of the clutching element 73 on the shaft 71 is under the control of a yoke 74 pivotally mounted at 75, and a spring 76 having one end fixed and its other end connected to the clutching element 73 tends to draw the clutching element 73 in the direction of the sleeve 72, so as to bring projections on the sleeve 72 and element 73 respectively, into clutching engagement, see Fig. 1.

Movement of the clutching element 73 toward the sleeve 72 by the spring 76 is prevented, with the parts in the position of Fig. 1, by means of a rod 77 pivotally connected to an arm 78 of the yoke 74. The lower end of the rod 77 is connected to one end of a lever 79, having its other end supported on a fixed pivot 80, with a roll 81 bearing on the under face of a cam 82 mounted on the drive shaft 26. The roll 81 is maintained in engagement with the face of cam 82 by means of the spring 76, pulling on the yoke 74, and the cam 82 is so timed that during a portion of each revolution of the drive shaft 26, upward movement will be imparted to the rod 77 to permit the spring 76 to draw the clutching element 73 into engagement with the sleeve 72, provided however that an envelope has been fed by the wheels 7.

The arrangement for preventing the engagement of the clutching element 73 with the sleeve 72, in the event of the failure of an envelope to feed, consists of a stop plunger 83 extending in the direction of a stop lug 84 provided on the yoke 74 when the latter is in the position shown in Fig. 1. As long as the plunger 83 remains in this position, its engagement by the lug 84 will prevent the yoke 74 from turning about its pivot 75 to the dotted line position, even when the yoke is released by the cam 82, and is otherwise free to move in response to the pull of the spring 76. The plunger 83 is carried by a piston 83a, shown in dotted lines, within a cylinder 85 and a pipe 86 leading to the cylinder 85 is adapted to exhaust the cylinder and cause withdrawal of the plunger 83 to the dotted line position of Fig. 1.

For the purpose of exhausting the cylinder 85, a suitable source of suction is provided, such as for example, a cylinder 87 having a piston 88 therein connected to an eccentric 89 mounted on the end of the drive shaft 26. A pipe 90 leads from the cylinder 87 to a port 91 provided in the feed plate 8, the port 91 being adjacent a similar port 92 connected to the end of the pipe 86 leading from the cylinder 85. As best shown in Fig. 2, the ports 91 and 92 are connected by a groove 93 provided on the front face of the plate 8 with which the envelopes come into contact. In the absence of an envelope in engagement with the plate 8, movement of the piston 88 in the cylinder 87 merely sucks in air through the open port 91. However, with an envelope 4 held in engagement with the plate 8, the ports 91 and 92

92 will be covered, so that suction created in the cylinder 87 will be transmitted to the cylinder 85 through the pipes 93 and 86, and the groove 93 between the covered plate ports 91 and 92. As a result, the cylinder 85 can be exhausted to retract the plunger 83 only when an envelope is delivered to the feed plate 8.

As previously pointed out, the feed wheels 7 are adapted to feed an envelope 4 downwardly against the plate 8 at the beginning of a cycle of operations resulting from one complete revolution of the drive shaft 26. The eccentric 89 operating the piston 88 in the cylinder 87 is so timed that suction is being created at the port 91 at about the time of the arrival of an envelope 4 at the plate. Consequently, before the transfer disk 15 engages the envelope preparatory to moving it onto the anvil 19, the exhaustion of air from the cylinder 85 results in retraction of the plunger 83. The cam 82 controlling the yoke 74 is so timed that following the retraction of the plunger 83, the yoke 74 is free to turn under the pull of the spring 76 to permit shifting of the clutching element 73 into engagement with the sleeve 72, which at that time is stationary. Following engagement of the clutching element 73 with the sleeve 72, rotative movement is imparted to the sleeve 72 by the chain 72a through the previously mentioned Geneva motion, which is best shown in Figs. 3 and 4.

The chain 72a for driving the sleeve 72 passes around teeth formed on the periphery of a disk 94 loosely mounted on the drive shaft 26, and the radial slots 95 of the disk 94 are adapted to receive diametrically opposed rolls 96 mounted on a driving member 97, see Fig. 4. The member 97 of the Geneva motion is mounted for free rotation on a countershaft 98 spaced from and extending parallel to the drive shaft 26, and a gear 99 carried by the member 97 is driven from the shaft 26 through a pinion 100 on the shaft 26 and an interposed idler gear 101. The ratio between the teeth on the pinion 100 and on the gear 99, and between the teeth on the Geneva disk 94 and on the sleeve 72, is such that with the shaft 71 clutched to the sleeve 72, the shaft 71 will be turned through one complete revolution, and then come to rest during substantially one-half of a revolution of the main drive shaft 26. This is due to the fact that the driving member 97 of the Geneva motion makes only one-half of a revolution for each complete revolution of the drive shaft 26.

Therefore, the above described driving arrangement for the sleeve 72 results in the sleeve 72 being turned through one complete revolution during only a portion, substantially one-half, of the operating cycle represented by one complete revolution of the drive shaft 26. The cam 82 controlling the clutching element 73 is so timed that following the delivery of an envelope to the feed plate 8 and the withdrawal of the stop plunger 83, as previously described, the element 73 will be moved into clutching engagement with the sleeve 72, while the latter is still stationary. The shaft 71 having been clutched to the sleeve 72, the following rotation of the sleeve 72 through one complete revolution causes a complete cycle of operation of the fastener attaching devices driven from the shaft 71. The sleeve 72 thereupon comes to rest, as a roll 96 disengages the Geneva disk 94, after which the cam 82 turns the lever 79 to impart downward movement to the rod 77, and cause the latter to turn the yoke 74 and disengage the clutching element 73 from the sleeve 72.

When the yoke 74 is moved from the dotted line position to the full line position of Fig. 1 to disengage the clutching element 73, as just described, the end of the stop lug 84 engages a bevel surface 83b on the plunger 83, thereby forcing the plunger 83 into the cylinder 85 to permit movement of the lug 84 to a substantially vertical position. The plunger 83 thereupon returns to the position shown in Fig. 1, under the pressure of a spring, shown in dotted lines, acting on piston 10 83a, in which it remains until its retraction by suction upon the delivery of an envelope to the feed plate 8 at the beginning of an operating cycle. From the foregoing, it is apparent that the shaft 71 for driving the fastener attaching devices is normally disconnected from the continuously rotating drive shaft 26, and cannot be connected thereto unless an envelope is actually delivered to the feed plate 8 for transfer to the anvil 19 by the disk 15. Upon the positioning of an envelope 4 upon the anvil 19 with its seal flap 4a extended, as indicated in dot and dash lines in Fig. 5, the envelope remains stationary during the dwell between the rotative movements of the transfer disk 15; and the shaft 71 is turned through one complete revolution during this period to cause a full cycle of operation of the fastener attaching devices, as will next be described.

Fastener attaching devices

30

As best shown in Fig. 3, the table 1 carries on the left hand side of the anvil 19 a pair of reciprocating punches 102 and 103 spaced from each other in a horizontal plane in which also lies the transfer disk 15 when the latter is in engagement with an envelope. The punches 102 and 103 provide operating heads 102a and 103a connected by a rod 104 for reciprocatory movement in unison by means of a link 105 connected to a crank 106. The crank 106 is carried by one end of a shaft 107 rotatably mounted on the table 1, the other end of the shaft 107 being connected through bevel gears 108 to the intermittently operated shaft 71. The table 1 also carries a third punch 109 on the right hand side of the anvil 19 in axial alignment with the punch 103, the punch 109 providing a head 110 suitably slotted to receive a roll 111 carried at the end of a crank 112 mounted on a shaft 113. The shaft 113 is driven through bevel gears 114 from the shaft 71, and the gearing and cranks 106 and 112 are so arranged that one complete revolution of the shaft 71, following the feeding of an envelope 4 as previously described, imparts a complete reciprocatory movement to the several punches 102, 103 and 109.

As best shown in Fig. 1, vertical guideways 115 are provided in line with the several punches 102, 103 and 109 to lead a corresponding number of washer strips 116 from supply reels 116a mounted under the table 1, see Fig. 2, to cooperating pairs of feed rolls 117 mounted on suitable brackets above the several punches. The feed rolls 117 above the punches 102 and 103 respectively, are connected for rotation in unison by a shaft 118, 65 which is extended to carry a ratchet wheel 119 engaged by a pawl 120 carried by a swinging arm 121 mounted freely on the shaft 118. The arm 121 is connected to a link 122 actuated by a cam 123 mounted on the left hand punch operating shaft 107, the cam 123 being so timed that the washer strips 116 are fed upwardly in advance of the operation of the punches 102 and 103. The feed rolls 117 over the right hand punch 109 are similarly driven from the other punch actuating 70 75

shaft 113 by a cam 123' acting through a link 122' to advance the pawl 119'. Each of the punches 102, 103 and 109 has associated therewith an auxiliary punch 124 movable in unison therewith in the same vertical plane, as shown in Fig. 1. Each punch 124 serves to perforate the corresponding washer strip 116, the perforations thus formed being alined with the corresponding punches 102, 103 and 109 upon upward feeding of the strips 116 by the rolls 117.

10 Metallic eyelets 125 are adapted to be applied to the punches 102 and 109 by eyelet guides 126, see Fig. 9, which are supplied from suitable hoppers, not shown, these hoppers being under the control of rods 127 actuated by cams 128 mounted on the shaft 71 to cause delivery of eyelets to the guides 126. Each eyelet guide 126 has associated therewith a delivery mechanism actuated by a rod 129 operated from a cam 130 on the shaft 71. 15 Each of these rods 129 serves to deliver one eyelet at a time to the lower end of a guide 126 in a manner more fully shown and described in Patent No. 1,558,065 issued October 20, 1925, to Urbanowitz.

20 As best shown in Fig. 9, the anvil 19 is supported by the table 1 with a clearance between its left hand vertical face and the dies cooperating with the punches 102 and 124 to permit positioning of the body portion of the envelope over the anvil by the transfer disk 15. Therefore, the punch 102 by its operation is adapted to remove a metal eyelet 125 from the guide 126 and carry it with a washer cut from the strip 116 to the body of the envelope through which the eyelet is forced 25 by the punch 102 against a setting die 131 carried by the anvil 19. An even greater clearance is left between the right hand vertical anvil face and the dies cooperating with the punches 109 and 124 to permit positioning of the flap 4a of the envelope in extended position, and also to permit the string feeding devices to be moved into cooperative 30 relation with the punch 109 so as to feed a string 132 through an aperture previously made in the strip 116 by the auxiliary punch 124 below punch 109.

35 As best shown in Fig. 2, the string feeding device consists of a conical nose 133 carried at the end of an arm 134 turnable with a shaft 135 extending above the punch 109 and parallel thereto, see Fig. 3. The other end of the shaft 135 carries an arm 136 pivotally connected to a link 137 extending downwardly and carrying a roll 138 bearing on a cam 139 carried by the shaft 71. The shaft 71 also carries a cam 140 for actuating a bar 40 141, to operate a string gripper, hereinafter referred to, and another cam 142 on shaft 71 serves to operate a rock shaft 143 connected to a rod 144, which actuates a string feeding mechanism on the arm 134 through a rack 145, indicated in Fig. 40 2. As the construction and operation of the string feeding and gripping devices referred to above are all fully shown and described in the aforesaid Patent No. 1,558,065, a brief statement of the cycle of operations resulting from one revolution of the shaft 71 after an envelope has been placed on the anvil 19 by the transfer disk 15 will suffice for the purposes of the present application.

45 After an envelope 4 has been positioned on the anvil 19, by the transfer disk 15, with its body portion covering the solid anvil die 131 and its extended flap 4a covering the open anvil die 131a, the shaft 71 is turned through one complete revolution, in response to the functioning of the previously described detecting device which permits

5 the clutching element 73 to engage the sleeve 72 before the latter is driven through the Geneva motion from the main shaft 26. As the shaft 71 rotates, the punches 102, 103 and 109 start to move towards the envelope from both sides of the anvil 19 and the several washer strips 116 are fed upwardly to bring the perforations formed in said strips by the preceding operation of the auxiliary punches 124 in line with the axes of the approaching punches. At the same time, the 10 string feeding arm 134 is advanced from the position shown in Fig. 2, so that its nose 133 enters an aperture 146 formed in a plate 147 on which the feed rack 145 is mounted, see Fig. 9. At this time it will be understood that an aperture formed 15 in the washer strip 116 by the auxiliary punch 124 and an eyelet 125 in the guide 126 are axially alined with the approaching punch 109. However, before the punch 109 has been advanced sufficiently to remove an eyelet, the string 132 is fed 20 through the washer strip perforation by the operation of the rack 145 for seizure by gripping jaws 148 under control of cam 140 and bar 141, whereupon the arm 134 is swung to move the nose 133 out of the path of the approaching punch 25 109. The feeding arm 134 being held momentarily in this position, the gripping jaws 148 are opened and the punch 109 advances to remove an eyelet 125 from the guide 126 and position it in the perforation in the washer strip. Since the 30 perforation in the washer strip is a close fit for the eyelet 125, the string 132 previously fed through the perforation from the nose 133 is jammed between the eyelet 125 and the edge of the perforation, and thereby held securely enough to retain it 35 in position. Immediately upon the string being retained in the washer strip by the eyelet, the punch 109 continues its forward movement to punch a washer from the strip and carry it and the attached eyelet and string toward the flap 4a 40 of the envelope.

45 At the same time the punch 103 on the opposite side of the anvil is advanced to punch a washer from its strip in cooperation with the anvil die 131a, this washer being held on the end of the punch 103 by a projection 149 adapted also to receive the eyelet 125 on punch 109 and set the same after it has been forced through the envelope flap by the punch 109 cooperating with punch 103. This setting operation forces the 50 eyelet through the washer carried by punch 103, and thus secures washers on either side of the flap 4a of the envelope, with one end portion of the string 132 securely clamped between the eyelet and the washer on the outer flap surface, and with a slack portion of the string running to the nose 133.

55 During the setting of an eyelet 125 in the envelope flap 4a in the manner just described, the punch 102 advances to remove an eyelet from the corresponding guide 126, and continued motion of the punch 102 forces this eyelet through a washer perforation. The punch 102 thereafter punches a washer from the strip 116, and carries both washer and eyelet against the body portion 60 of the envelope, as supported by the left hand anvil face, to force the eyelet through the envelope wall against the setting die 131. The setting of the eyelets 125 and washers on both the envelope body and flap occur substantially simultaneously. 65

70 By the time that the eyelets have been set in the envelope, the string feeding arm 134 reaches a fully retracted position, shown in dotted lines in Fig. 2, thereby carrying a portion of the string just beyond the nose 133 between the then opened 75

blades 150 of a cutting device mounted adjacent to the shaft 71. Just after the string has been positioned between the opened blades 150, a cam 151 on the shaft 71 operates the blades to sever the string 122 in a manner fully set forth and described in the aforesaid Patent No. 1,558,065. The operation of the cutting blades 150 occurs at substantially the same time that the envelope is released by backward movement of the several punches 102, 103, 109 and 124, and as the punches reach their fully retracted position at the end of the operating cycle, the shaft 71 comes to rest. The transfer disk 15 is thereupon rotated in a counterclockwise direction, as viewed in Fig. 3, to withdraw the envelope from the anvil 19 with the washers, eyelets and string attached thereto. The withdrawal movement of the envelope by the disk 15 is sufficient to fully clear the flap 4a from the anvil, the loose length of the string carried by the flap extending downwardly from the flap, so that it clears all parts of the machine, the movement of the completed envelope being limited by gage 69, as described above. Obviously, continued rotation of the drive shaft 26 will cause the stops 10 to be withdrawn from the slots 11 in the guide plate 9 by operation of the rod 47, whereupon the completed envelope will fall in the space between the feed plate 8 and guide plate 9 until its lowermost edge is engaged by the belts 21, and the envelope conveyed thereby to the stack, as shown in Fig. 1.

As soon as the shaft 71 comes to rest, the clutching element 73 is withdrawn from the then stationary driven sleeve 72 by the yoke 74, and all the punches 102, 103, 109 and 124 remain in their retracted positions, awaiting the initiation of the next operating cycle. However, as previously pointed out, the shaft 71 will not be connected to the Geneva motion, as operated from the shaft 26, until after the next envelope has been actually fed downwardly by the selectors 7a, and has been properly positioned by the stops 10 for movement onto the anvil 19 by the transfer disk 15.

45 Adjustment and operation of the machine

In setting up the machine for operation on envelopes of a given size, the stop fingers 10 are first vertically adjusted in the slots 11, so as to arrest the downward movement of each envelope with its center line exactly in alignment with the center line of the anvil 19, as shown in Fig. 5. This insures that the cooperating punches and dies will accurately apply the eyelets and washers to the center of the rear wall of the envelope and the substantial center of the extended flap 4a. It will also be noted that the transfer disk 15 lies substantially in the horizontal plane in which the cooperating pairs of punches operate, so that for any given setting of the stop fingers 10 in the slots 11, the transfer disk 15 will engage the arrested envelope on the stop fingers substantially along its center line.

As best shown in Figs. 6 and 8, the cross shaft 13 on which the arms 12 carrying the stops 10 are mounted is rotatably supported at its ends in bearing brackets 152 vertically adjustable on the guide plate 9. Each bracket 152 provides a vertically disposed slot 153 for receiving a retaining bolt 154 threaded into any one of a number of openings 155 provided in the plate 9. Since each slot 153 spans the distance between adjacent openings 155 in the plate 9, the cross shaft 13 carrying the stops 10 can be closely adjusted over a wide range to accurately position the several

stops 10 and register envelopes of different widths with the axis of the anvil 19.

With the stops 10 properly set, the gage 69 is next adjusted longitudinally of the anvil 19, so that when an envelope supported by the stops 10 is projected onto the anvil 19 by the transfer disk 15, the gage will arrest the movement of the envelope with its extended flap and rear wall exactly in register with the cooperating sets of punches of the fastener attaching mechanism. The withdrawal stop gage 69 is adjusted on its bracket 70, so that the gage will limit movement of a completed envelope as it is withdrawn from the anvil 19 by turning of the transfer disk 15 in the opposite direction. The gage 69 is set so that the envelope flap 4a will be fully withdrawn from the anvil with the loose length of string carried by the flap extending downwardly to clear the fastener attaching mechanism, and the envelope body will therefore fall freely to the stacking device when released by the stops 10.

As previously pointed out, the invention also contemplates counting the completed envelopes handled by the machine and to this end, there is provided an arrangement for stacking the envelopes in such a manner that one envelope of a predetermined number, or group, will extend further from the stack than the remaining envelopes of the group. As best shown in Figs. 9, 10 and 11, the bracket 70 carrying the swiveled holder 70a for the gage 69 is pivotally mounted about a vertical axis on pins 156, so that swinging of the bracket 70 in a clockwise direction as viewed in Fig. 9, will withdraw the gage 69 from the feed plate slot 69a, as indicated in dotted lines. Normally the bracket 70 is maintained in the position shown in Fig. 9 with its gage extending through the slot 69a by a spring 157 pressing on an arm 158 turnable with the bracket 70, and as long as the gage 69 remains in this position, the completed envelopes will be stacked evenly, as indicated in Fig. 2.

As best shown in Fig. 9, the arm 158 carried by the gage bracket 70 is pivotally connected to one end of a rod 159, the other end of which provides a forked portion 159a embracing a shaft 160 on which is mounted a cam 161. The forked portion 159a carries a roll 162, and the spring 157 acting on the arm 158 yieldingly maintains the roll 162 in engagement with the surface of the cam 161. A ratchet wheel 163 is turnable with the cam 161 and as best shown in Fig. 10, an arm 164 turnable freely on the shaft 160 carries a pawl 165 adapted to engage with the ratchet teeth 163a. The free end of the pawl 165 carrying arm 164 is pivotally connected by a link 166 to the extended end of the rod 104 carrying the punch heads 102a and 103a, so that each movement of the punches 102 and 103 to the right causes the pawl 165 to turn the ratchet wheel 163 and cam 161 through the displacement of one ratchet tooth.

The cam 161 is so designed that its surface is circular except for a projection 161a extending for the displacement of one ratchet tooth 163a. Consequently, as the cam 161 is turned with a step-by-step movement in cooperation with the punch 102, no turning movement will be imparted to the gage holder 70, and the gage 69 will remain in the position shown in Fig. 9. However, when a number of completed envelopes corresponding to the number of ratchet teeth 163a has passed through the machine, the cam projection 161a moves the rod 159 to the right, thereby turning the bracket 70 in a clockwise direc-

tion to withdraw the gage 69 from its slot 69a into the dotted line position. When this occurs, the next completed envelope withdrawn from the anvil 19 by the transfer disk 15 will move beyond 5 the position previously occupied by the gage 69, as the disk 15 completes its turning movement without slippage of the friction plates 15a, and obviously when the envelope controlled by the full turn of the disk 15 is stacked, it will project 10 further from the stack than the remainder of the envelopes in a given group. As shown in Fig. 10, the ratchet wheel 163 provides twenty-five teeth 163a, so that one envelope in every twenty-five will project from the pile of envelopes in the 15 stacking device 20, as shown in Fig. 1, although obviously the number of envelopes in each group may be varied as desired. Upon the succeeding operation of the punch 102 following the withdrawal of the gage 69, the roll 162 returns to the 20 position shown in Fig. 10, thereby restoring the gage 69 to its original position. Since the envelope counting mechanism is operated directly by one of the fastener punches and the operation of the entire fastener attaching mechanism is 25 in turn dependent upon the feed of an envelope, it necessarily follows that only completed envelopes are counted during the operation of the machine.

From the foregoing, it is apparent that by the 30 present invention there is provided a machine entirely automatic in its operation for removing flat blanks, such as envelopes, from a supply, and presenting them one by one for the attachment of washers, eyelets and a string to the rear 35 wall and extended flap of each envelope. Following the attachment of the fastening devices to an envelope, it is withdrawn and released for conveyance to the stacking device, one envelope out of each group projecting from the stack for 40 convenient counting and packing. While the machine is adapted to make one complete cycle of operations for each revolution of the drive shaft, the feeding of washer strip, eyelets and string is automatically dependent upon the actual 45 arrival of an envelope at the transfer station, thereby eliminating possible clogging of the machine by washers, eyelets and string, upon failure of an envelope to feed.

I claim:

50 1. In a machine of the class described, the combination with means for supporting on edge a supply of flat blanks such as envelopes, an anvil disposed in a vertical plane below said envelope supply, means for feeding strip material on opposite sides of said anvil and parallel thereto, and punches operating at right angles to said anvil for forming washers from said strip, of means for removing envelopes one by one from said supply and guiding each envelope for free 55 downward movement in the plane of said anvil, means for arresting such downward movement of each envelope in register with said anvil and spaced therefrom, and means for shifting each envelope from its arrested position onto said anvil for the attachment of washers thereto.

2. In a machine of the class described, the 60 combination with means for supporting on edge a supply of flat blanks such as envelopes, an anvil disposed in a vertical plane below said envelope supply, means for feeding strip material on opposite sides of said anvil and parallel thereto, and punches operating at right angles to said anvil for forming washers from said strip, of means for removing envelopes one by 65 one from said supply and guiding each envelope

for free downward movement in the plane of said anvil but spaced therefrom, means for arresting such downward movement of each envelope with its center line coinciding with the center line of said anvil, and means for shifting each envelope 5 from its arrested position onto said anvil for the attachment of washers thereto by said punches, as well as for withdrawing each envelope from said anvil following the attachment of said washers. 10

3. In a machine of the class described, the combination with means for supporting on edge a supply of flat blanks such as envelopes, an anvil disposed below said envelope supply, means for feeding strip material on opposite sides of said 15 anvil and parallel thereto, and punches operating at right angles to said anvil for forming washers from said strip, of means for removing envelopes one by one from said supply and guiding each envelope for free downward movement 20 in the plane of said anvil but spaced therefrom, means for arresting such downward movement of each envelope with its center line coinciding with the center line of said anvil, and means for shifting each envelope from its arrested position onto said anvil for the attachment of washers thereto by said punches, as well as for withdrawing each envelope from said anvil following the attachment of said washers, said strip feeding means and said punches being automatically 25 maintained in an inoperative condition until after the arrival of an envelope in register with said anvil.

4. In a machine of the class described, the combination with a support for a supply of flat 30 blanks, such as envelopes, means for removing envelopes one by one from said supply, an anvil displaced from the line of movement of said envelopes, and means for bringing each envelope to rest in the plane of said anvil, of an oscillatory transfer member adapted to engage each envelope and means for positively arresting movement of an envelope in either direction by said transfer member. 45

5. In a machine of the class described, the combination with a support for a supply of flat blanks on edge, such as envelopes, means for removing envelopes one by one from said supply and guiding each envelope for free downward movement, an anvil displaced in a vertical plane from the line of movement of said envelopes, and means for bringing each envelope to rest in the plane of said anvil, of an oscillatory transfer member adapted to engage each envelope and move it onto said anvil and gaging means carried by said anvil for positively determining the position of the envelope thereon.

6. In a machine of the class described, the combination with a support for a supply of flat 60 blanks, such as envelopes, means for removing envelopes one by one from said supply, an anvil displaced from the line of movement of said envelopes, and means for bringing each envelope to rest in the plane of said anvil, of an oscillatory transfer member adapted to engage each envelope and move it onto and off of said anvil, and gaging members carried by said anvil and a stationary portion of said machine for positively limiting movement of an envelope onto or off of 70 said anvil.

7. In a machine of the class described, the combination with a support for a supply of flat blanks, such as envelopes, means for removing envelopes one by one from said supply, an anvil 75

- displaced from the line of movement of said envelopes, and means for bringing each envelope to rest in the plane of said anvil, of an oscillatory transfer member adapted to engage each envelope and move it onto and off of said anvil, and gaging members carried by said anvil and a stationary portion of said machine for positively limiting movement of an envelope onto or off of said anvil, said transfer member being frictionally driven to prevent buckling of an envelope upon engagement with a gaging member.
8. In a machine of the class described, the combination with means for supporting on edge a supply of flat blanks such as envelopes, means for removing envelopes one by one from said supply and for guiding each envelope for free downward movement, an anvil displaced in a vertical plane from the line of movement of said envelopes, and means for bringing each envelope to rest in the plane of said anvil, of an oscillatory transfer member adapted to engage an envelope in its arrested position and move it onto and off of said anvil, with said envelope remaining stationary on said anvil during a dwell in the oscillatory movement of said transfer member.
9. In a machine of the class described, the combination with means for supporting on edge a supply of flat blanks such as envelopes, means for removing envelopes one by one from said supply and for guiding each envelope for free downward movement, an anvil displaced in a vertical plane from the line of movement of said envelopes, and means for bringing each envelope to rest in the plane of said anvil, of an oscillatory transfer member adapted to be first moved into engagement with an envelope in its arrested position, then to shift said envelope onto said anvil, then to withdraw said envelope from said anvil, with a dwell in the oscillatory movement of said member during which it remains on the said anvil.
10. In a machine of the class described, the combination with a support for a supply of flat blanks such as envelopes, means for removing envelopes one by one from said supply, an anvil displaced from the line of movement of said envelopes, and means for bringing each envelope to rest in the plane of said anvil, of a transfer disk pivotally mounted about one axis to engage and disengage an envelope in its arrested position, and rotatably mounted about another axis to move an envelope onto and off of said anvil.
11. In a machine of the class described, the combination with a support for a supply of flat blanks such as envelopes, means for removing envelopes one by one from said supply, an anvil displaced from the line of movement of said envelopes, and means for bringing each envelope to rest in the plane of said anvil, of a rotatably and pivotally mounted transfer disk adapted to be swung into engagement with an envelope in its arrested position and by its rotation first in one direction and then in the other to move an envelope onto and off of said anvil.
12. In a machine of the class described, the combination with a support for a supply of flat blanks, such as envelopes, an envelope stacking device, means for feeding flexible strip, cooperating punches for forming washers from said strip, dies cooperating therewith, means for removing envelopes one by one from said supply and means for presenting each envelope to the operation of said punches and dies for the attachment of washers thereto, as well as for withdrawing each envelope from said punches and dies following the attachment of washers thereto, of means for conveying each complete envelope to said stacking device, and means comprising a gaging member responsive to the operation of said punches for permitting offsetting of an envelope in the stack following the delivery of a predetermined number of completed envelopes thereto.
13. In a machine of the class described, the combination with a support for a supply of flat blanks, such as envelopes, an envelope stacking device, means for feeding flexible strip, punches for forming washers from said strip, dies cooperating therewith, means for removing envelopes one by one from said supply and means for presenting each envelope to the operation of said punches and dies for the attachment of washers thereto, as well as for withdrawing each envelope from said punches and dies following the attachment of washers thereto for delivery to said stacking device, of a gaging member adapted to register each completed envelope with said stacking device, and means controlled by said fastened attaching devices for rendering said gaging member inoperative after a predetermined number of envelopes have been delivered to said stacking device.
14. In a machine of the class described, the combination with means for applying a string and a string anchoring device to the flap and body of an envelope, envelope feeding means, arresting means and transfer means, of means dependent upon the feeding and arrestation of an envelope for controlling the operation of said string and anchorage applying means upon a transferred envelope.
15. In a machine of the class described, the combination with means for applying a string and a string anchoring device to the flap and body of an envelope, of automatically cooperating envelope feeding means, arresting means and stacking means.
16. In a machine of the class described, the combination with means for applying a string and a string anchoring device to the flap and body of an envelope, of continuously operating envelope feeding means, arresting means and stacking means, with said string and anchorage applying means operating only when an envelope is detected at the arresting station.
17. In a machine of the class described, the combination with means for applying a string and a string anchoring device to the flap and body of an envelope, of automatically cooperating envelope feeding means, arresting means, stacking means and counting means.
18. In a machine of the class described, the combination with means for applying a string and a string anchoring device to the flap and body of an envelope, of automatically cooperating envelope feeding means, arresting means, stacking means and counting means, said envelope feeding, arresting and stacking means operating continuously, with said string and anchorage applying means and said counting means operating only when an envelope is detected at the arresting station.

VINCENT E. HEYWOOD.
